UNITED STATES PATENT OFFICE.

MATTEO COSULICH, OF NEW YORK, N. Y., ASSIGNOR TO THOMAS & BUCKLEY HOISTING CO., OF NEW YORK, N. Y., A CORPORATION OF NEW YORK.

BRAKE FOR ELECTRIC-MOTOR-OPERATED HOISTS.

Application filed October 27, 1921. Serial No. 510,703.

To all whom it may concern:

Be it known that I, MATTEO COSULICH, a citizen of the United States, and resident of the borough of Manhattan, city, county and State of New York, have invented certain new and useful Improvements in Brakes for Electric-Motor-Operated Hoists, of which the following is a specification.

This invention relates to improvements in automatically acting brakes for electric-motor-operated hoisting apparatus designed to prevent dropping of the load when the motor circuit is broken.

As is well known, the armature shaft of an electric motor is free to rotate in either direction when the motor circuit is broken, and it is therefore necessary in electric-motor-driven hoists to provide means for preventing the pull of the load on the hoisting cable from unwinding the cable from the drum when the motor is stopped after the load has been elevated to the desired point, or when the circuit is broken from any other cause, such as the blowing 25 of a fuse.

The object of the present invention is to provide a simple, efficient, and quick-acting brake which will automatically release the motor shaft and permit it to freely rotate when current is supplied to the motor to raise a load, and which will instantly lock the motor shaft if said shaft should start to rotate in the reverse direction.

In the drawing:

Figure 1 is a fragmentary side elevation of a well-known type of electric-motor-operated hoisting apparatus provided with the improved automatic brake;

Fig. 2 is a side elevation of the brake mechanism;

Fig. 3 a section on the line 3—3 of Fig. 2;

Fig. 4 an edge view of the upper end of the standard on which the brake-shoes are supported;

Figs. 5 and 6 perspective views of the two links which connect each shoe with the supporting standard; and

Fig. 7 a detail view showing the inner face of one of the brake shoes.

Referring to the drawing by numerals 1 designates the electric motor upon the armature shaft 2 of which is fixed a pulley 3, said pulley being connected by a belt 4 with a pulley 5 on a counter shaft 6. A pinion 7 on shaft 6 meshes with a gear 8 on a shaft

9, and the hoisting drum 10 upon which the hoisting cable 11 is wound is also mounted on shaft 9. The foregoing parts constitute part of a well known form of electric motor driven hoisting apparatus. It will be understood that the usual drum-releasing clutch, not shown, is provided for permitting lowering of the hoisting tackle by gravity, and it will also be obvious that the improved brake may be applied to other types of electric motor driven hoists than the one shown.

The outer end of the armature shaft 2 of the motor is journalled in a bearing in the head 14 of a standard 15, which standard is rigidly held by bolts 16 to the bed 17 of the hoisting apparatus. A suitable bushing 18 surrounds shaft 2 within the head 14. The exterior of head 14 is of general cylindrical bilged form, and a brake drum 12 is held to shaft 2 adjacent the inner end of said head by a key 13. The drum 12 has a circumferential flange 19 overhanging head 14, the internal friction surface of which flange is concentric with the axis of shaft 2 and the drum.

A pair of segmental brake shoes 20, preferably having their contact faces covered with a suitable friction material 21, are shiftably held to the head 14 within the drum, the outer contact faces of said shoes being curved on the same arc as the inner face of the flange 19 of the drum. Each shoe 20 is supported by a pair of parallel links 22 and 23, the outer ends of said links engaging in recesses 25 in the inner face of the shoe and being pivotally held to the shoe by pins 24 having a tight driving fit in apertures 32 in the shoe and extending loosely through apertures 33 in the links. The inner ends of the links engage in recesses 26 in the head 14 of standard 15 and are pivotally held to said head by pins 27 having a tight driving fit in apertures 34 in the head and extending loosely through apertures 35 in the links.

The two brake shoes engage the flange 19 at diametrically opposed points, and the pair of links supporting one of the shoes extend downwardly and outwardly from one side of head 14 while the pair of links supporting the other shoe extend upwardly and outwardly from the head. The drum 12 rotates in the direction indicated by the arrow in Fig. 2 when the motor is energized

to elevate a load, and coil springs 28 engaged in recesses 29 in projections 30 on links 22 and in recesses 31 in head 14 normally swing the links about the pivot pins 5 27 in the opposite direction, thereby yieldably urging the brake shoes 20 substantially radially outward against the internal surface of the flange 19 of the brake drum.

It will be obvious that when current is 10 supplied to motor 1 to cause cable 11 to be wound upon the hoisting drum 10 and lift a load, the brake drum 12 will be free to rotate in the direction indicated by the arrow in Fig. 2, as springs 28 will yield and only 15 hold the shoes 20-21 in light frictional engagement with flange 19 of the brake drum. If, however, the motor circuit is broken, the pull of the load on cable 11 will start to rotate motor shaft 2 and the brake drum 12 in 20 the reverse direction, whereupon springs 28 and the frictional contact of the drum flange 19 with shoes 20 will rock the links about pivots 27 in a counter clockwise direction and cause the shoes to move radially outward and bind tightly against the inner surface of flange 19. The reverse rotation of the drum will thus be stopped almost instantly as a very slight outward movement of the brake shoes will cause the same to 25 exert a powerful braking action on the drum. The stopping of the brake drum 12 and shaft 2 will, of course, prevent further unwinding of the cable 11 as the hoisting drum 10 is geared up with shaft 2.

30 The brake shoes engage the brake drum at substantially diametrically opposite points and the thrust from these shoes, when they engage the brake drum, is in opposite directions directly against the armature shaft bearing, and is therefore completely balanced. This is quite essential in apparatus of this kind. The armature must run true and all lateral thrust on the armature 35 bearings and on the armature shaft must be

either avoided or completely balanced in 45 order that the armature shaft shall be maintained in proper alignment. Electrically operated hoisting apparatus is subject to very hard usage and the armature shaft would soon be out of true alignment unless the 50 sudden shocks and stresses due to the automatic operation of the armature lock or brake are not balanced or neutralized.

It will be evident that the load will be arrested after a very slight downward movement thereof and before it acquires any momentum, thus avoiding injurious shocks to the hoisting apparatus. Slipping will be impossible, even with very heavy loads, 55 since the greater the weight of the load the tighter the shoes will be forced outward against the flange 19 of the brake drum.

What I claim is:

In an electric motor operated hoisting apparatus, the combination of a brake drum 60 fixed on the armature shaft and having an internal braking surface concentric with the shaft, two brake shoes within the drum and arranged to engage the drum at diametrically opposite points, a stationary support 65 forming a bearing for the armature shaft, a pair of outwardly extending links within the drum at each side of the said support, one link of each pair being tangential, 70 means pivotally connecting the inner ends 75 of the links of each pair to said support at opposite sides thereof, means pivotally connecting a brake shoe with the outer ends of the links of each pair, and spring means 80 normally tending to swing the links in one direction to bring the brake shoes into engagement with the brake drum, whereby the thrust of the brake shoes will be in opposite 85 directions and will be balanced on the said bearing support.

In testimony whereof I hereunto affix my signature.

MATTEO COSULICH.
